ABSTRACT

8-Thiomethylergolines, prolactin inhibitors.

6 Claims, No Drawings

temperature of if desired by heating to a temperature in the range from room temperature to 100°C. The products of the reaction are customarily isolated by standard techniques and purified by chromatography, preferably over Florisil. The compounds of this invention in which R is H are prepared by hydrolysis in base of the corresponding compound in which R is

The compounds of this invention are white crystalline solids and form pharmaceutically acceptable salts with nontoxic acids. These pharmaceutically acceptable salts are included within the scope of this invention. Non-toxic acids useful in forming the salts of this invention include such inorganic acids as hydrochloric acid, nitric acid, phosphoric acid, sulfuric acid, hydrobromic acid, hydriodic acid, nitrous acid, phosphorus acid and the like, as well as non-toxic organic acids including aliphatic mono and dicarboxylic acids, phenyl-substituted alkanoic acids, hydroxy alkanoic and alkanedioic acids, aromatic acids, aliphatic and aromatic sulfonic acids, etc. Such pharmaceutically-acceptable salts thus include sulfate, pyrosulfate, bisulfate, sulfite, bisulfite, nitrate, phosphate, monohydrogenphosphate, dihydrogenphosphate, metaphosphate, pyrophosphate, chloride, bromide, iodide, fluoride, acetate, propionate, decanoate, caprylate, acrylate, formate, isobutyrate, caprate, heptanoate, propiolate, oxalate, malonate, succinate, suberate, sebacate, fumarate, maleate, butyne-1,4-dioate, hexyne-1,6-dioate, benzoate, chlo-

In each experiment the rats were killed by decapitation, and 150 μl aliquots of serum were assayed for prolactin. Each male rat received an intraperitoneal injection of 2.0 mg of reserpine in aqueous suspension 18 hours before administration of the ergoline derivative. The purpose of the reserpine was to keep prolactin levels uniformly elevated. The derivatives were dissolved in 10% ethanol at a concentration of 10 $\mu\text{g}/\text{ml}$, and were injected intraperitoneally at a standard dose of 50 $\mu\text{g}/\text{kg}$. Each compound was administered to a group of 10 rats, and a control group of 10 intact males received an equivalent amount of 10 percent ethanol. One hour after treatment all rats were killed by decapitation, and the serum was collected and assayed for prolactin as previously described. The results were evaluated statistically using Student's "t" test to calculate the level of significance, "p."

The difference between the prolactin level of the treated rats and prolactin level of the control rats, divided by the prolactin level of the control rats gives the percent inhibition of prolactin secretion attributable to the compounds of this invention. The table which follows gives prolactin inhibition percentages for a series of compounds coming within the scope of Formula II above. In the table, column 1 gives the name of the compound; column 2, the dose level of the compound in the prolactin inhibition test; column 3, the percent prolactin inhibition; and column 4, the level of significance.

The invention is further illustrated by Examples 1-6 which follow.

Table

Name of Compound	Dose	% Prolactin Inhibition	"p" Value
D-6-methyl-8-phenylmercapto-methyl-9,10-didehydroergoline	10 μg	50	<.05
D-6-methyl-8-methylmercapto-methyl-9,10-didehydroergoline	10 μg	62	<.01
D-6-methyl-8-acetylthiomethyl-ergoline	10 μg	40	<.01
D-6-methyl-8-mercaptopromethyl-ergoline	10 μg	66	<.001
D-6-methyl-8-methylmercapto-methylergoline	10 μg	49	<.001
D-2-chloro-6-methyl-8-methyl-mercaptopromethylergoline	10 μg	46	<.001
D-6-methyl-8-thiocyanomethyl-ergoline	10 μg	41	<.001
D-6-methyl-8-acetylthiomethyl-9,10-didehydroergoline	10 μg	44	<.01

robenzoate, methylbenzoate, dinitrobenzoate, hydroxybenzoate, methoxybenzoate, phthalate, terephthalate, benzenesulfonates, toluenesulfonate, chlorobenzene-sulfonate, xenesulfonate, phenylacetate, phenylpropionate, phenylbutyrate, citrate, lactate, β -hydroxybutyrate, glycolate, malate, tartrate, methanesulfonate, propanesulfonates, naphthalene-1-sulfonate and naphthalene-2-sulfonate and like salts.

The compounds of this invention are useful as prolactin inhibitors. The inhibition of prolactin secretion by the compounds of this invention is evidenced by the following experiment: Adult male rats of the Sprague-Dawley strain weighing about 200 g. were used. All rats were housed in an air-conditioned room with controlled lighting (lights on 6 a.m. - 8 p.m.) and fed lab chow and water ad libitum.

55

EXAMPLE 1

Preparation of
D-6-Methyl-8-Thiocyanomethylergoline

A reaction mixture was prepared from 2 g. of D-6-methyl-8-p-toluenesulfonyloxymethylergoline, 2 g. of sodium thiocyanate and 100 ml. of dimethylsulfoxide (DMSO). The mixture was heated in the range 60 100°-110°C. for 4.5 hours. The reaction mixture was then cooled and poured over an ice water mixture. 6-Methyl-8-thiocyanomethylergoline was insoluble in water and precipitated. The solid was collected by filtration and melted at about 181°-3°C. with decomposition after recrystallization from an ether-hexane solvent mixture.

Analysis: Calc.: C, 68.65; H, 6.44; N, 14.13; S, 10.78; Found: C, 68.31; H, 6.66; N, 13.99; S, 10.48.

65

5

EXAMPLE 2

Preparation of

D-6-methyl-8-phenylmercaptomethylergoline

A suspension of 10 g. of D-6-methyl-8-hydroxymethylergoline in 200 ml. of pyridine was prepared. To this suspension was added slowly a solution containing 6.0 ml. of methanesulfonyl chloride and 200 ml. of pyridine. The resulting mixture was stirred at room temperature under a nitrogen atmosphere for about one half hour and was then poured into 2.5 l. of saturated aqueous sodium bicarbonate. The alkaline aqueous layer was diluted to 6 liters with water, and the diluted layer allowed to stand at room temperature. D-6-methyl-8-mesyloxymethylergoline formed in the above reaction slowly crystallized. The solution was chilled to about 0°C. in order to cause more of the compound to precipitate. The solution was then filtered, and the filter cake recrystallized from ethanol. A further quantity of D-6-methyl-8-mesyloxymethylergoline was obtained by extracting the filtrate with ethyl acetate, separating the ethyl acetate layer and removing the ethyl acetate therefrom by evaporation in vacuo. Recrystallization of D-6-methyl-8-mesyloxymethylergoline prepared as above from ethanol yielded material melting at about 192°-4°C. with decomposition.

Analysis: Calc.: C, 61.05; H, 6.63; N, 8.38; S, 9.59; Found: C, 60.85; H, 6.46; N, 8.45; S, 9.30.

A solution of 2.5 ml. of thiophenol in 25 ml. of DMSO was prepared. 1.1 g. of sodium methylate were added. Next a solution of 700 mg. of D-6-methyl-8-mesyloxymethylergoline in 50 ml. of DMSO was added in drop-wise fashion to the sodium thiophenate solution. After the addition had been completed, the reaction mixture was stirred at room temperature under a nitrogen atmosphere for about 2 hours, and was then poured into a saturated aqueous tartaric acid solution. The acidic layer was extracted with chloroform. The chloroform extract was separated and discarded. The acidic layer was then made basic with the excess of 14N ammonium hydroxide, and the resulting alkaline layer extracted with chloroform. The chloroform extract was separated and dried. Evaporation of the chloroform left a residue which was dissolved in ethyl acetate. The ethyl acetate solution was thoroughly washed with water followed by a wash with saturated aqueous sodium chloride solution. The ethyl acetate layer was dried. Removal of the ethyl acetate by evaporation in vacuo yielded a residue comprising D-6-methyl-8-phenylmercaptomethylergoline which was recrystallized from ethanol and melted at 194°-5°C. with decomposition. The compound was then dissolved in chloroform and chromatographed over florisil (25 g.). The chromatogram was developed with a chloroform-methanol (19:1) solvent mixture. Fractions containing D-6-methyl-8-phenylmercaptomethylergoline as determined by thin layer chromatography were combined. Evaporation of the solvent from the combined fractions and recrystallization of the resulting residue from an ether-hexane solvent mixture yielded D-6-methyl-8-phenylmercaptomethylergoline: MP=195°-6°C. with decomposition.

Analysis: Calc.: C, 75.82; H, 6.95; N, 8.04; S, 9.20; Found: C, 75.85; H, 6.69; N, 7.97; S, 9.19.

Following the above procedure D-6-methyl-8-mesyloxymethyl-9,10-didehydroergoline was reacted

6

with thiophenol to yield D-6-methyl-8-phenylmercaptomethyl-9,10-didehydroergoline which melted at about 200°-3°C. with decomposition after recrystallization from methanol.

Analysis: Calc.: C, 76.26; H, 6.40; N, 8.08; S, 9.25; Found: C, 76.02; H, 6.42; N, 7.99; S, 9.02.

The corresponding maleate salt was prepared by dissolving the compound in tetrahydrofuran and adding an equivalent amount of maleic acid also in tetrahydrofuran. The maleate salt melted at 198°-9°C. after recrystallization from methanol.

Analysis: Calc.: C, 67.51; H, 5.67; N, 6.06; S, 6.93; Found: C, 67.29; H, 5.89; N, 5.79; S, 6.71.

EXAMPLE 3

Preparation of

D-6-methyl-8-methylmercaptomethylergoline.

Ten milliliters of dimethyl formamide (DMF) were cooled to about 0°C. 1 ml. of methanethiol was added followed by 1.0 g. of sodium hydride as a 50 percent suspension in mineral oil in portions. The resulting mixture was stirred for about 1 hour and then allowed to warm to room temperature. Then, following the procedure of Example 2, a solution of 1 g. of D-6-methyl-8-mesyloxymethylergoline in 50 ml. of DMF was added in drop-wise fashion to the sodium salt of methanethiol. The resulting product was isolated and purified by the procedure of Example 2 to yield D-6-methyl-8-methylmercaptomethylergoline melting at about 153°-5°C. Recrystallization of the compound thus obtained (omitting the chromatographic purification step of Example 2) from an ether-hexane solvent mixture yielded D-6-methyl-8-methylmercaptomethylergoline, MP = 153°-4°C.

Analysis: Calc.: C, 71.28; H, 7.74; N, 9.78; S, 11.19; Found: C, 71.08; H, 7.59; N, 9.83; S, 10.99.

Following the above procedure D-6-methyl-8-methylmercaptomethyl-9,10-didehydroergoline was prepared from the corresponding 8-mesyloxymethyl derivative by reaction with methylmercaptan. The compound melted at 181°-3°C. with decomposition after recrystallization from ether-hexane solvent mixture.

Analysis: Calc.: C, 71.79; H, 7.09; N, 9.85; S, 11.27; Found: C, 72.01; H, 6.84; N, 9.62; S, 11.27.

The corresponding maleate salt was prepared by dissolving the compound in ether and adding an equivalent amount of maleic acid also in ether. Maleate salt melted at 159°-160°C. with decomposition.

Analysis: Calc.: C, 62.98; H, 6.07; N, 6.99; S, 8.01; Found: C, 62.99; H, 6.13; N, 6.78; S, 7.86.

EXAMPLE 4

Preparation of

D-6-methyl-8-acetylmercaptomethylergoline

Following the procedure of Example 2, thioacetic acid (as the sodium salt) was reacted with D-6-methyl-8-mesyloxymethylergoline in DMF solution to yield D-6-methyl-8-acetylmercaptomethylergoline which was isolated and purified by the procedure of that example. Chromatography of the crude product over florisil using chloroform containing 2 percent ethanol as eluent yielded purified D-6-methyl-8-acetylmercaptomethylergoline MP=153°-5°C. with decomposition.

Analysis: Calc.: C, 68.75; H, 7.05; N, 8.91; S, 10.20; Found: C, 68.70; H, 7.22; N, 8.62; S, 10.47.

Following the above procedure, D-6-methyl-8-acetylmercaptopethyl-9,10-didehydroergoline was prepared from the corresponding 8-mesyloxymethyl compound. The purified compound thus prepared melted in the range 165°-7°C. with decomposition after recrystallization from an ether-hexane solvent mixture.

Analysis: Calc.: C, 69.20; H, 6.45; N, 8.97; S, 10.26; Found: C, 69.48; H, 6.71; N, 9.00; S, 10.56.

The corresponding maleate salt was prepared by dissolving the base in ether and adding an equivalent amount of maleic acid in ether. The maleate salt melted at 178°-9°C. with decomposition.

Analysis: Calc.: C, 61.67; H, 5.65; N, 6.54; S, 7.48; Found: C, 61.95; H, 5.50; N, 6.84; S, 7.63.

D-2-chloro-6-methyl-8-acetylmercaptopethylergoline was also prepared by the above procedure. Recrystallization of the residue remaining after combining fractions from chromatography shown to contain D-2-chloro-6-methyl-8-acetylmercaptopethylergoline by thin layer chromatography, using a solvent mixture of ether and hexane or recrystallization yielded purified material melting at 40°-1°C.

Analysis: Calc.: C, 61.97; H, 6.07; N, 8.03; S, 9.19; I, 10.16; Found: C, 61.75; H, 5.78; N, 7.75; S, 9.41; I, 10.32.

EXAMPLE 5

Preparation of D-6-methyl-8-mercaptopethylergoline

A reaction mixture containing 1.0 g. of D-6-methyl-acetylmercaptopethylergoline (from Example 4), 0.0 ml. of ethanol and 100 ml. of 4N aqueous hydrochloric acid was refluxed under a nitrogen atmosphere for five and one-half hours. The reaction mixture was cooled and made basic with an excess of 14N ammonium hydroxide. The aqueous alkaline layer was extracted with chloroform, and the chloroform yielded a residue comprising D-6-methyl-8-mercaptopethylergoline formed in the above reaction. The residue was chromatographed over 75 g. of florisil using chloroform containing 5 percent ethanol as the eluant. D-6-methyl-8-mercaptopethylergoline was identified in chromatographic fractions by thin layer chromatography as a more polar, and therefore more slowly moving, material than starting material. Fractions containing D-6-methyl-8-mercaptopethylergoline were combined and recrystallized from ethanol. The compound thus purified melted at 255°-7°C. with decomposition.

Analysis: Calc.: C, 70.55; H, 7.40; N, 10.28; S, 11.77; Found: C, 70.31; H, 7.65; N, 10.04; S, 12.00.

The above procedure was repeated except that methanethiol was used in place of thioacetic acid for reaction with D-2-chloro-6-methyl-8-mesyloxymethylergoline to form D-2-chloro-6-methyl-8-methylmercaptopethylergoline. Chromatography over florisil of the residue obtained by combining chromatographic fractions shown to contain the desired material using an ether-hexane mixture for recrystallization yielded purified D-2-chloro-6-methyl-8-methylmercaptopethylergoline melting at 194°-5°C.

Analysis: Calc.: C, 63.63; H, 6.60; N, 8.73; S, 9.99; I, 11.05; Found: C, 63.42; H, 6.55; N, 8.47; S, 10.12; I, 11.35.

EXAMPLE 6

Preparation of D-6-methyl-8-thiocyanomethyl-9,10-didehydroergoline

A reaction mixture containing 2.16 g. of D-6-methyl-8-mesyloxymethyl-9,10-didehydroergoline (prepared from the corresponding 8-hydroxymethyl derivative by the procedure of Example 2), and 2 g. of sodium thiocyanate in 100 ml. of DMSO was heated at a temperature in the range 50°-70°C. under a nitrogen atmosphere for about one hour, and then for an additional hour in the range 70°-100°C. The reaction mixture was cooled, diluted with water, and the aqueous layer extracted with ethyl acetate. The ethyl acetate layer was separated and filtered to remove an insoluble purple decomposition product. The ethyl acetate layer was washed with water and with saturated aqueous sodium chloride, and was then dried. The solvent was removed therefrom by evaporation in vacuo. The resulting residue was chromatographed over 30 g. of florisil using an eluant composed of chloroform containing 15 percent ethanol. Fractions shown to contain D-6-methyl-8-thiocyanomethyl-9,10-didehydroergoline (formed in the above reaction) by thin layer chromatography were combined, the solvent removed therefrom, and the resulting residue rechromatographed over florisil using chloroform as an eluant. Again, fractions shown to contain

D-6-methyl-8-thiocyanomethyl-9,10-didehydroergoline by thin layer chromatography were combined and the solvent removed therefrom by evaporation. Recrystallization of the resulting residue from an ether-hexane solvent mixture yielded purified D-6-methyl-8-thiocyanomethyl-9,10-didehydroergoline melting at about 190°-1°C. with decomposition.

Analysis: Calc.: C, 69.12; H, 5.80; N, 14.22; S, 10.85; Found: C, 69.03; H, 5.85; N, 14.40; S, 11.32.

Being prolactin inhibitors, the compounds of this invention are also potentially useful for suppressing the growth of breast adenocarcinomas in female mammals. For example, D-6-methyl-8-thiocyanomethylergoline has demonstrated an ability to suppress the growth of adenocarcinomas induced by administration of dimethylbenzanthracene in female rats at a dose level of 1.2 mg/kg. The compound is administered to the female rat suspended in corn oil, although it would also be practicable to administer the compound in the form of a pharmaceutically-acceptable acid addition salt in aqueous solution.

We claim:

1. A compound of the formula:

wherein

R is H, CN,

phenyl, or alk;
 R' is H, Cl, or Br;
 alk is C₁-C₃ alkyl; and
 R'' and R''' when taken singly are H; and, when
 taken together with the carbon atoms to which they
 are attached, form a double bond or a non-toxic,
 pharmaceutically-acceptable acid addition salt
 thereof.

2. A compound according to claim 1, said compound being D-6-methyl-8-phenylmercaptomethyl-9,10-didehydroergoline.
- 5 3. A compound according to claim 1, said compound being D-6-methyl-8-methylmercaptomethyl-9,10-didehydroergoline.
4. A compound according to claim 1, said compound being D-6-methyl-8-methylmercaptomethylergoline.
- 10 5. A compound according to claim 1, said compound being D-6-methyl-8-thiocyanomethylergoline.
6. A compound according to claim 1, said compound being D-6-methyl-8-acetylmercaptomethylergoline.
